UNITED STATES PATENT OFFICE

ARTHUR O. AUSTIN, OF BARBERTON, OHIO, ASSIGNOR, BY MESNE ASSIGNMENTS, TO THE OHIO BRASS COMPANY, OF MANSFIELD, OHIO, A CORPORATION OF NEW JERSEY

SERIES TRANSFORMER CONNECTION

Application filed July 2, 1926. Serial No. 120,088.

This invention relates to high tension transformer systems and has for its object the provision of an improved arrangement of transformers which will produce an addition of the secondary voltages of the transformers while maintaining unimpaired regulation and providing for increased power output and which will permit economical construction and operation.

10 The invention is exemplified in the combination and arrangement of parts shown in the accompanying drawings and described in the following specification and it is more particularly pointed out in the appended 15 claims.

In the drawings—

Fig. 1 is a diagrammatic view of transformer connections according to one embodiment of the present invention.

20 Figs. 2 and 3 are views similar to Fig. 1 showing different embodiments of the invention.

It is a difficult matter to construct and arrange a single transformer for exceedingly 25 high voltages as the maximum voltage or tension to ground requires an abnormal amount of clearance or insulation compared to that required for transformers of lower voltage. The chain or concatenated connection of transformers in which each transformer is energized from the preceding 30 transformer in the chain permits the tying together of transformers in series so that the voltages are additive. This arrangement permits of obtaining a very high voltage with individual transformers built for 35 moderate voltages.

In the concatenated or chain system of connection however as illustrated, for instance, in United States Patent 1,523,367 the KVA (kilovolt-ampere) output of the chain is limited to the KVA output of the smallest or most highly loaded transformer in the series or chain. In other words, if there are 45 four transformers having 500 KVA output each, the maximum KVA output would be limited to 500 KVA. If one of the transformers in the series had only 300 KVA output when the transformer was developing 50 its maximum rated current or voltage, the

KVA output of the series would be limited to this figure.

In my improved method of connecting up transformers it is possible greatly to increase the KVA output of the series thereby permitting the use of smaller transformers for a given total KVA output. With the improved method, it is also possible to obtain a much better regulation which is beneficial in case the transformers are desired for power purposes or for determining the voltage on the high side for test purposes.

In Fig. 1 are shown two transformers with cores 8 and 9, secondaries 10 and 11 and corresponding primaries 12 and 13. The end of the winding 10 is electrically connected to the case and core at 14. The secondary of the other transformer is electrically connected to its case and core at 15 and the points 14 and 15 are electrically connected together. The primaries 12 and 13 of the transformers are electrically connected at one end to the core and case which will maintain a definite difference in voltage between the other end of the winding and core and case. The primary 75 windings 12 and 13 are shown connected in multiple, but it is evident that these windings may be connected in any of the usual ways. The winding of the secondary 10 is brought out through a high voltage bushing at 16 and connected to ground. The other end of the secondary winding 10 which is connected to the case and core at 14 is connected at 15 to the end of the secondary 11. The other end of the secondary 11 is brought out through a 80 high voltage bushing at 17. Assuming that the transformers will each develop 500 K. V., it will be possible to develop 1,000 K. V. with this arrangement without placing any more electrical stress on the parts of the transformer than would be obtained were the 85 transformers used singly. In order to do this it is, of course, necessary to insulate the transformers from ground so that they will both carry the voltage developed in the winding 10 of the first transformer. The generator used for exciting the transformers will also have to be insulated for this same voltage. This is a comparatively easy matter as the generator may be driven by an insulated 90

95

100

105

belt such as a rubber belt or through an insulated coupling. If the generator is provided with a motor which can be operated by air, oil, dry steam or other non-conductor 5 which is caused to flow through an insulating hose or tube, the motor operating the generator may be operated directly with the generator.

It is evident that if the two cores were combined into one, the arrangement shown in Fig. 1 corresponds to a single transformer with the center point grounded. It will be seen with this arrangement that a transformer which is ordinarily wound for half voltage 10 to ground and has the middle of the high potential winding electrically connected to the case can be operated at full voltage to ground by the above method where the case is insulated from ground. In general, it is 15 cheaper to build transformers which have the high voltage winding grounded on the core and case in the center rather than at one end, as the voltage between secondary and core and case is only half what it is where one 20 end of the secondary is grounded as in Fig. 1.

In Fig. 2 is shown an arrangement of transformers where the center of the high voltage winding in one transformer is connected to the case and core, whereas the end 25 of the high voltage secondary winding of the other transformer only is connected to its case and core, although the two transformers are arranged so that their voltage will be accumulative as in the case of Fig. 1.

In Fig. 2 two generators are used as there will be a very appreciable difference in voltage between the cores and cases in the two transformers. In the arrangement shown in Fig. 2 the frame of generator 18 may be 30 grounded, thus making this generator easy to control as to voltage and general operation. Generator 19 operating the second transformer must be insulated as the difference in voltage between this generator and ground 35 would be the voltage generated in the secondary winding 20 plus $1/2$ the voltage generated in the secondary winding 21. The two generators may be kept in synchronism by driving through synchronous motors which 40 are driven from the same power source, the synchronous motors being rigidly coupled to the generators 18 and 19 so that proper phase relation will be maintained. For most work it is not even necessary that the two 45 generators be driven in synchronism at all times. If one of the generators is connected to a variable speed motor it is possible to so regulate the speed that the voltage in the two transformers may have proper phase relation. This may be determined very simply 50 by any one of several well known synchronism indicating devices.

In all cases where an insulated generator is used it, of course, is necessary to insulate 55 the exciter or to use a storage battery for ex-

citation which may be readily insulated. If the voltage of the generator 19 is set for a given value, it is usually possible to control the voltage of the series within the limits desired by controlling the voltage of the generator 18 which may be operated as any generator, as the frame or winding is grounded.

Fig. 3 shows another arrangement of transformers where one transformer has one end of the secondary 30 electrically connected to the core and case and the other transformer has the center of the secondary 31 electrically connected to the core and case. While in general the voltage will be less on the generator of the last mentioned transformer than 70 on the generator 33 of the first mentioned transformer, both generators will be under considerable voltage. It, of course, is evident that the arrangement is applicable 75 where one end of each secondary on the transformers in series is electrically connected to its core and case or where the center points of the secondary windings are connected to the core and case.

The arrangements described above have 80 the advantage among others that the maximum KVA output may be increased with the addition of more transformers. Practically any number of transformers may be used in series as the resulting regulation will be the same as that for a single transformer under the same conditions. There is a decided advantage with the present invention where the accurate determination of voltage is desired 85 as the phase displacement will not be so great and the regulation will be much better than in chain or auto type connections. The scheme permits the use of any high voltage 90 transformer in a series without the necessity of providing special windings. With the arrangement it is possible greatly to increase 95 the KVA output of a series of ordinary transformers over that possible where the exciting or energizing current must be drawn through a single member in the group. Where the 100 generators can be insulated, the scheme has an application for power line work as it will permit the increase in voltage by adding 105 transformers to those already in service. Numerous schemes which are already in use 110 for synchronizing the generators may be 115 readily used for maintaining the proper phase relation of the several generators.

I claim—

1. A pair of transformers each comprising 120 a primary and a secondary winding, said transformers having their secondary windings connected in series, the adjacent ends of said secondary windings in said series being grounded on the cores and cases of said transformers and a generator conductively connected with the primary windings of said transformers for energizing said transformers, said generator being insulated from 125

ground and having one terminal thereof grounded on said cores and cases.

2. A pair of transformers each comprising a primary and a secondary winding, said 5 transformers having their secondary windings connected in series, the adjacent ends of said secondary windings in said series being electrically connected directly to the cores and cases of said transformers while the end 10 of one of said secondary windings at one extremity of said series is grounded and a generator conductively connected with the primary windings of said transformers for energizing said transformers, said generator 15 having one terminal thereof directly connected electrically to the cores and cases of said transformers.

3. In combination a plurality of transformers, each comprising a primary and a 20 secondary winding, said transformers having their secondary windings connected in series, and a generator conductively connected to the primary of one of said transformers, said generator having one terminal thereof conductively connected with the secondary windings of said transformers at a point between 25 said windings, said generator having its frame insulated from ground.

In testimony whereof I have signed my 30 name to this specification on this 26th day of June A. D. 1926.

ARTHUR O. AUSTIN.
